STAND FOR DETACHABLY MOUNTING
FRAMES AND CASINGS

James Edgar Vineent Winterbourne, London, England, assignor to S. Smith & Sons (England) Limited, London, England, a British company

Application April 17, 1946, Serial No. 662,894
In Great Britain March 26, 1945

5 Claims. (Cl. 58—56)

1

This invention relates to stands for detachably mounting frames and casings, such, for example, as are employed for clocks, pictures, mirrors, and other fittings which require to be supported on a base, and of the kind in which the fitting is mounted in an opening in a holder, for example, in an opening between two uprights spaced apart and secured to a base. An object of the invention is to facilitate detachment of the fitting from the stand without dismantling the stand and without the provision of unsightly connections.

According to this invention, there is provided a stand for the accommodation and support of a clock or similar article, which article is provided with pins projecting from either side thereof. The stand comprises a base and two spaced uprights fixed to the base, inwardly directed projections on said uprights, each of which projections is formed with an inwardly facing slot closed at its upper end but open at its lower end, the clock or similar article being disposed between said uprights and the pins respectively engaging within said slots, said stand also comprising retaining means adapted to hold said pins against the closed ends of the slots.

The said retaining means may either comprise a packing piece detachably secured to the base, or a set-screw extending through the base so as to engage with the bottom of the fitting.

Preferably, the lengths of the slots are such that when the fitting has been raised by said retaining means, the pins are held securely against the ends of the slots.

The following is a description of a number of embodiments of the invention, reference being made to the accompanying drawings, in which:

Figure 1 is a front elevation of a clock mounting showing one of the uprights partly in section;

Figure 2 is a section on the line 2—2 of Figure 1 looking in an upward direction;

Figure 3 shows the position of the clock when assembled it with the uprights;

Figure 4 is a similar view to Figure 3 of an alternative form of mounting; and

Figure 5 shows the position of the clock when assembled with the mounting of Figure 4.

As will be seen from Figure 1, the clock mounting comprises two uprights 10 secured to or formed integral with a base 11. At their upper ends the uprights are provided with two inwardly directed portions 12 having downwardly directed faces 13. Extending upwardly from these faces are slots 14 which are arranged to accommodate pins 15 fixed to the clock casing 16 and which terminate short of the top of the uprights. In

2

order to assemble the clock in the uprights it is tilted into the position shown in Figure 3, and then slipped into position with the pins 15 immediately below the open ends of the slots 14.

5 It may then be raised and when the pins are at or near the tops of the slots the clock may be tilted into the position shown in Figure 1. If it is desired to maintain the pins tight against the tops of the slots they are of such a length as to leave a gap between the base 11 and the lower part of the casing into which may be slid a packing piece 17 which may be wedge-shaped and may be maintained in position by screws 18.

In cases where it is not practicable to tilt the 15 clock the spacing of the downwardly directed faces 13 from the base 11 may be such as to permit the pins 15 to pass beneath them, as shown in Figure 4, when the clock is upright, and after raising them to the tops of the slots they may be 20 maintained in that position either by a packing piece, as shown in Figure 1, or by a screw 19 engaging a threaded hole in the base, as shown in Figure 5.

I claim:

25 1. A clock comprising a base, two spaced uprights fixed to the base, inwardly directed projections on said uprights, each of which projections is formed with an upwardly extending slot closed at its upper end, a clock-case disposed between said uprights and having pins on either side thereof engaging said slots and retaining means adapted to hold said pins against the closed ends of said slots.

35 2. A clock comprising a base, two spaced uprights fixed to the base, inwardly directed projections on said uprights, each of which projections is formed with an upwardly extending slot closed at its upper end, a clock-case disposed between said uprights and having pins on either side thereof engaging said slots and retaining means disposed between the base and the bottom of the case so as to hold the case in a position in which said pins abut the closed ends of said slots.

45 3. A clock comprising a base, two spaced uprights fixed to the base, inwardly directed projections on said uprights, each of which projections is formed with an upwardly extending slot closed at its upper end, a clock-case disposed 50 between said uprights and having pins on either side thereof engaging said slots, and a packing piece between the base and the bottom of the case and of such size as to hold the case in a position in which the pins abut the closed ends of the slots.

4. A clock comprising a base, two spaced uprights fixed to the base, inwardly directed projections on said uprights, each of which projections is formed with an upwardly extending slot closed at its upper end, a clock-case disposed between said uprights and having pins on either side thereof engaging said slots, a set screw extending up through a threaded hole in the base and engaging the bottom of the case so as to hold the case in a position in which the pins abut the closed ends of the slots.

5. A clock comprising a base, two spaced uprights fixed to the base, inwardly directed projections on said uprights each of which projections is formed with an upwardly extending slot, a clock-case the height of which is greater than its fore-and-aft dimension, two pins projecting on opposite sides of the casing and at a greater distance from the bottom thereof as is the distance of the bottom of the projections from the base, which pins are engageable with said slots

15
5 by tilting the clock-case and introducing in between the uprights while moving the case bodily upwards and retaining means disposed between the base and the bottom of the case when the case is disposed upright so as to hold the case in a pattern in which the pins abut the closed ends of the stops.
